UNITED STATES PATENT OFFICE.

BUCKLEY H. HOLMES AND J. HUSS RALSTON, OF GOSHEN, INDIANA.

TYPE-CLEANING DEVICE FOR TYPE-WRITING MACHINES.

SPECIFICATION forming part of Letters Patent No. 443,830, dated December 30, 1890.

Application filed August 20, 1890. Serial No. 362,482. (No model.)

To all whom it may concern:

Be it known that we, BUCKLEY H. HOLMES and J. HUSS RALSTON, citizens of the United States, residing at Goshen, in the county of 5 Elkhart, in the State of Indiana, have invented a new and useful Type-Cleaning Device for Type-Writing Machines in which the Type are Attached to Movable Rods or Bars, of which device the following is a specification.

Our invention relates to improvements in type-cleaning devices for type-writing machines; and it consists in the construction, 15 novel combination, and adaptation of devices hereinafter described and claimed.

In the accompanying drawings, Figure 1 is a vertical section of the brush with its attachments. Fig. 2 is a plan of the brush. Fig. 3 is a cross-section of brush. Fig. 4 is 20 the brush and attachments shown in operative connection with a type-writing machine. Similar letters refer to similar parts throughout the several views.

The cleaning device or brush may be of 25 any soft substance adapted to such uses; but it is preferably a brush with stiff bristles made by setting the bristles in the outer rim of a horizontally-placed disk or frame of the necessary shape to allow the bristles to come 30 in contact with the faces of the type in a type-writing machine at each upward and downward motion of the brush. In the machines in which the type-basket is round the brush would be made circular, and where the type-basket is oval the brush should be of suitable 35 shape to conform to it. In the drawings the brush is shown of a form adapted specially for use in the Remington type-writer No. 2, caligraph, and similar machines having an 40 oval type-basket.

In the drawings, A represents the brush, which is attached on the under side to a vertical rod B, which is pivoted to the end of a lever-bar C. This lever-bar is pivoted to a 45 fulcrum D. The fulcrum is attached at its base to a bar E, which is attached to the frame of the type-writing machine. The outer end F of the lever-bar C is flattened in suitable shape, so that the brush A may be 50 made to rise by the pressure exerted by the hand of the operator at the end F of the lever.

On removing the pressure, the brush, by its own weight, returns to the position shown by the dotted lines in Fig. 1, where it rests out of the way of the type when the type-writing 55 machine is being operated.

In operation, as will be readily seen, the type-cleaning attachment shown cleans the type by bringing the bristles of the brush A into frictional contact with the type-faces by 60 causing the brush to rise and fall by an alternating pressure on the outer end F of the lever C. To prevent the brush from varying from its true perpendicular motion where it is moved by an upward pressure from below, 65 as is done in the particular device shown in Fig. 1, upright standards G G are rigidly attached to the cross-bar E. These upright bars G G enter tubular collars or bearings H H, which are attached to the under side of the 70 brush A, and the brush-body is also perforated in the same line to allow the brush to be moved perpendicularly between the type-bars for a sufficient distance to allow of a free action of the brush.

In construction the form shown in the drawings is the simplest, and the lever device shown for giving the rising and falling motion to the brush is equally efficient with any other; but as the same motion may be produced by many common devices we do not care to limit ourselves to any specific means.

Such changes may be made in the construction of our improved device, to adapt the same for use in conjunction with various machines, as fairly fall within the scope of our 85 invention.

In the operation of the lever the device shown, in which the brush A is fixedly attached to the vertical rod B at the point a 90 and the fulcrum D is loosely attached to the cross-bar E at b, seems to produce the most satisfactory result; but substantially the same result may be effected by attaching the brush A loosely to the vertical rod B at the point a 95 and the fulcrum D fixedly to the cross-bar E at b, and we do not limit ourselves to the particular form of construction shown.

Having thus described our device, what we claim as our invention, and desire to secure 100 by Letters Patent, is—

In a type-writing machine, in combination

with its type and type-bars, a brush capable of being raised and lowered with a perpendicular motion by means of a lever, one end of which is attached to the brush and the 5 fulerum of which is attached to the frame of the machine, and upright standards also rigidly attached to the frame of the machine, entering bearings attached to the brush to guide

the brush, substantially as described, and for the purpose shown.

BUCKLEY H. HOLMES.
J. HUSS RALSTON.
